UNITED STATES PATENT OFFICE

HARRY S. FRANK, OF BROOKLYN, NEW YORK, ASSIGNOR TO VOCATIONAL ADJUSTMENT BUREAU, OF NEW YORK, N. Y., A CORPORATION OF NEW YORK

FUR-PIECE HANGER

Application filed April 25, 1930. Serial No. 447,119.

The invention relates to hanger devices, more especially to a new and useful improvement in a device adapted for suspending an elongated fur piece, as of an animal skin with 5 spring mouth or clip, and is intended to be worn over the shoulders or about the neck.

The invention has for its object a novel form of hanger device whereby a fur piece, through its said mouth, may readily and conveniently be secured and hung in a substantially 10 vertical position, and as conveniently removed therefrom when it is desired to again make use of the fur piece.

A further object of the invention resides 15 in the provision of a hanger device which will not injure the fur piece in any way and which is of itself of attractive design, compact and inexpensively constructed.

In carrying out the invention, a stuffed pad 20 or cushion of a soft, yielding and more or less elastic material has secured thereto at one end a retaining hook, as of wire; and there is provided intermediate its ends a transverse band or strap tensioned thereto 25 or spanned thereover as by being sewed thereon over portions of its length, the unsewed loop portion or portions then more or less tightly hugging the cushion.

The lower or under half of the opened 30 mouth of the fur piece is designed to be received then under the said strap, pressing backwardly the body material sufficiently to admit of the insertion, and the jaw or clip element accommodating itself therebetween 35 by the inherent pressure of the cushion.

The nature of the invention, however, will best be understood when described in connection with the accompanying drawings, in which:

40 Fig. 1 is a view in perspective illustrating the novel hanger device suspending a fur piece.

Fig. 2 is a side elevation of the hanger device; and Fig. 3 is a vertical section there- 45 through.

Referring to the drawings, the novel hanger embodies a pad or cushion of soft, self-adjusting material of the desired form and embodying the central or filler portion 10, 50 as of cotton, and which is overlaid with an

outer finishing cover or casing 11 of a suitable fabric or cloth such as velvet. As indicated, the pad is shown in the form of an elongated more or less cylindrical member reinforced by the longitudinal binding strip 55 12 which covers also a transverse circumscribing band or strap member 13, for example, of material similar to that of the casing. The said strap, moreover, is tensioned or spanned more or less about the pad intermediate its ends and is secured thereto over a part of its length, for example, at diametrically opposite portions, as indicated. This may conveniently be effected by sewing the strap to the cover or casing 11 to span or 60 stretch the same thereover and compress slightly thereby the cushion material of the pad, which is of a more or less pliable or resilient character so that an appreciable friction will be maintained between the strap and 65 body portion. It will be apparent, therefore, if the spring-urged lower jaw or clip element 14 of the head 15 of the animal skin or fur piece 16 be then inserted under an unsecured or loop portion of the strap that a 70 substantial hold will be effected between said jaw and the body portion of the pad by the said strap in addition to the spring holding action of the mouth clip itself in closing 75 thereover. Moreover, the outer surface 11 of the pad, comprising a cover or casing of relatively high grade material and of a more or less soft nature, will not injure or objectionably affect the material of the fur piece 16.

In order to then suspend or hang the entire device with fur piece attached, as aforesaid, the said pad is provided with, for example, a hook member 17 extending outwardly from the upper end thereof and designed 80 to be placed over or to ride upon a suitable supporting rod 18, hook or the like, as is well understood. The inner end of the hook 17 extends into the body material 10 of the pad and may be secured or held therein in any 85 convenient manner. For example, it may be formed into an eye 19, which is then embedded in the filler 10, and the casing material 11 closed over its shank. A reinforcing cap 90 piece 20 may also be sewed thereover, if de- 165

sired, to afford a finished appearance as well as to better secure the hook therein.

To remove the fur piece from the pad it is necessary merely to open the mouth 15 by pressing upon the clip and then drawing downwardly thereon to release the lower jaw from the holding strap 13. When not required, the hanger, being relatively small, may conveniently be stored away until again desired for use; and, if retained in a closet or the like, it does not occupy any great amount of space and, moreover, is not objectionable in appearance.

It will be appreciated that the hereinbefore described hanger affords an ideal device for maintaining the fur piece in a vertical position when not in use and which position is the proper one for an article of this character and one in which, furthermore, it will not be injured by other garments which may be hung therewith in the same closet. Moreover, it then occupies a minimum space in contradistinction to the usual manner of supporting fur pieces by folding or bending the same over a rod and in which position they not only occupy a disproportionate space but are subject to injury.

I claim:

1. A fur piece hanger, comprising a pad of soft, yieldable material, means extending therefrom to suspend the pad, and a strap mounted transversely of the pad and spanned thereover to receive and hold the jaw of an elongated fur piece.
2. A fur piece hanger, comprising a pad of soft, yieldable material, means extending therefrom to suspend the pad, and a pliable strap secured for a portion of its length to the pad and transversely thereof, the remainder being spanned thereover and adapted to receive and hold the jaw of an elongated fur piece.
3. A fur piece hanger, comprising a pad of soft, yieldable material, means extending therefrom to suspend the pad, and a strap encircling the pad and sewed thereto over diametrically opposite portions of its length, the remaining portions being adapted to receive and hold the jaw of an elongated fur piece.
4. A fur piece hanger, comprising a pad of soft, yieldable material, a cloth casing enclosing the same, suspension means extending from the pad, and a strap mounted transversely of the pad and spanned thereover to receive and hold the jaw of an elongated fur piece.
5. A fur piece hanger, comprising a pad of soft, yieldable material, means extending therefrom to suspend the pad, a reinforcing binding strip extending lengthwise of the pad, and a strap encircling the pad and secured over a portion of its length thereto and beneath the strip, the unsecured portion be-

ing adapted to receive and hold the jaw of an elongated fur piece.

6. A fur piece hanger, comprising a pad of soft, yieldable material, a hook member with one end located within said pad, the shank thereof extending through one end of the pad and formed with a suspension hook, and a strap mounted transversely of the pad and spanned thereover to receive and hold the jaw of an elongated fur piece.

7. A fur piece hanger, comprising a pad of soft, yieldable material, a hook member with one end located within said pad, the shank thereof extending through one end of the pad and formed with a suspension hook, a reinforcing cap about said shank and secured to the casing, a strap mounted transversely of the pad and spanned thereover to receive and hold the jaw of an elongated fur piece.

8. A fur piece hanger, comprising a pad of a filler of soft, yieldable material, a casing therefor of soft, yieldable material enclosing the filler, a reinforcing binding strip extending lengthwise of the casing, a hook member with one end located within the filler, the shank thereof extending through one end of the casing and formed with a suspension hook, a reinforcing cap about said shank and secured to the casing, and a strap encircling the casing and secured over a portion of its length thereto and beneath the said binding strip, the unsecured portion being adapted to receive and hold the jaw of an elongated fur piece.

In testimony whereof I affix my signature. 100
HARRY S. FRANK.
